WRAP STRIPE KNITTING MACHINE

Robert H. Lawson, Pawtucket, R. I., assignor to
Hemphill Company, Central Falls, Mass., a corporation of Massachusetts

Continuation of application Serial No. 552,954,
July 24, 1931. This application July 12, 1934,
Serial No. 734,847

6 Claims. (Cl. 66—135)

This invention relates to an improved method of and mechanism for knitting so-called wrap stripes in stockings or other fabric and more especially half hose.

In the drawings:

Fig. 1 is a view in front elevation, partly in section of a portion of a knitting machine with the improvements applied;

Fig. 2 is a fragmentary view in vertical elevation and partly in section, showing some of the mechanism for guiding the wrap stripe threads to the needles of a knitting machine;

Fig. 3 is a fragmentary view in section showing a portion of the mechanism shown in Fig. 2, the section being taken at a place other than the section shown in Fig. 2;

Fig. 4 is a view in section taken along the line 4—4, Fig. 2;

Fig. 4a is a fragmentary view corresponding to Fig. 4, but showing a later phase of the knitting cycle;

Fig. 5 is a plan view of the latch ring showing means for wrapping threads around needles, the wrapping means and needles being in one phase of the knitting cycle;

Figs. 6, 7, 8 and 9 are views showing the wrapping means and needles in successively later phases of the knitting cycle;

Fig. 10 is a fragmentary view in elevation showing one thread being wrapped around selected needles;

Fig. 11 is a view similar to Fig. 10 but showing another thread being wrapped around other and immediately adjacent selected needles; and

Fig. 12 is a view of a stocking or half-hose having integrally knitted therein and in adjacent wales of the same course or courses different wrap threads, as well as a heel and a toe.

The needle cylinder 1 is shown as being mounted for rotary movements in a circular base 2, a portion only of which is shown. Rotary movements are imparted to the cylinder in any convenient manner (not shown). Mounted upon the circular base 2 or part carried thereby is a cam 3, the purpose of which is to raise or position jacks that may have dropped below the level of selecting cams 4 and 5 so that the latter may select such jacks and consequently raise their needles for a purpose hereinafter to be described. A plurality of cams 4, three in the present instance, are mounted in diagonal slots 6 provided in a cam block 7, the slots 6 being cut through the block 7 and the open ends thereof being closed by means of a cap plate 7'. By removing the cap plate 7' the cams 4 may be replaced as

desired. As shown, the block 7 is connected to another cam block or support 8 within which are mounted the beforementioned cams 5 circumferentially spaced from the cams 4, eight such cams 5 being shown in the present instance, although the number of cams 4 and 5 may be varied at will. The cams 5 are arranged in diagonally disposed slots 9, the slots 9 being cut through the block 8 and the open ends of such slots being closed by the block 7.

By selectively controlling the cams 4 and cams 5 which constitute needle selecting stations, a variable number of needles can be elevated to have wrapped therearound either the thread 25 or the thread 25', one example of such varied needle wrapping being illustrated in Fig. 12.

The cam block 8 depends from and is carried by a stationarily supported cam plate 10, upon the upper face of which are mounted a cam block 11, and a cam ring 12, which cam ring and block constitute or carry certain cams for actuating the needles. The instep cams 13, 13' are mounted in any convenient manner (not shown) upon the upper face of the cam plate 10 which latter also supports a cam 14, the function of which will be hereinafter described. The usual sinker head 15 is provided for actuating the sinkers (not shown). Thereabove is mounted a latch ring 16 pivotally supported in the usual manner for movements to and from the needle cylinder and carrying a plurality of thread guiding levers such as 17, 18 and 19, which levers feed the main or body threads to the needles as well as heel and toe, striping or other threads, either singly or in plating relation, as desired. As shown, Fig. 5, a body thread 20 and a plating thread 21 are being fed to the needles, the heel and toe thread 22 being shown in an inoperative, non-feeding position. In said Fig. 5 a few needles 23 only are shown, the needle circle being otherwise indicated by a dot and dash line 24.

In order to wrap threads, such as 25, 25', around selected needles, the said threads are supported from elevated bobbins mounted upon a plate or support 26 such as that shown in the Lawson Patent 1,702,608, February 19, 1929, and from such elevated bobbins the threads pass down through holes 27 provided in the gear 28, through aligning holes 29 in a supplemental plate 30 fast to the gear plate 28, and then down through holes 31 provided in a plate 32, fastened to and depending from the lower side of which is a block or plate 33, the said block or plate 33 being fastened to the plate 32 by means of pins or screws 34. The block 33 is also pro-

vided with holes 35 aligning with the holes 31 and through which the threads 25, 25' pass to and through eyelets 36, 36' carried by a yoke 37 and finally down through other eyelets 38, 38' mounted between and carried by two plates 39 and 40.

The gear 28 and parts carried thereby are mounted in bearings provided by a flanged ring 41 which is stationarily supported on a bracket 42, and to which ring 41 is connected in any suitable manner a complementary flanged ring 43 which latter overhangs the gear plate 28 and limits the upward thrust thereof. The gear plate 28 is driven in any suitable manner such as by means of the usual drive including the shaft 44 which may be driven in any suitable manner such for example as the means for driving the shaft 45 in Lawson Patent 1,702,608, said shaft 45 corresponding to shaft 44 herein disclosed. The gear plate 28 is provided with a sleeve or tubular extension 45 upstanding therefrom, to the upper end of which is connected a plate 46, which plate 46 is adapted to support thread guiding eyelets for threads passing from bobbins which may be supported upon and rotatable with plate 26 as hereinbefore described, such plate being mounted upon and rotatable with the gear plate 28. The bobbins, yarn tensions, etc., are not herein shown in detail as they may be of substantially the same construction as are the corresponding parts shown in Fig. 32 of the Lawson Patent 1,702,608.

All the rotary parts included in the wrapping mechanism may be referred to as constituting a wrapping head which is eccentrically mounted with respect to the needle cylinder and is rotatable in time therewith thereby causing the thread such as 25, 25' to move from a position within the needle circle to a position to the outside thereof and back again to a position within the needle circle. Although the wrapping head is rotatable in time with the needle cylinder, the linear speed of the rotating needles is greater than the linear speed of the wrap threads by reason of the larger diameter of the needle cylinder as compared with the diameter of the wrapping head.

One object of the present invention is to so control the wrapping that immediately adjacent needles may be wrapped with threads of different colors and during the same course of knitting. One means for accomplishing that object is disclosed in Figs. 2, 4, and 4a, the method of knitting being more or less diagrammatically disclosed in Figs. 5-11 inclusive, to which several figures reference will now be made.

As hereinbefore stated the disc 30 is attached to the underside of the gear 28 in any suitable manner so as to move therewith, and to the underside of the said disc is attached, as by means of screws 47, a flanged sleeve 48 which loosely surrounds the shaft. To the lower end of the sleeve 48 is attached a collar 49 as by means of a screw 50. Pivotal connected to the flange 51 of the sleeve 48 as by means of screws 52 are arms or detents 53 and adjacent to the outer end of each arm at 54 is connected a coil spring 55 the other end of which is made fast to a pin 56 depending from flange 51 of sleeve 48. Intermediate the ends of each detent 53 there is provided a depending pin in the form of a screw 57, each said pin engaging a slot 58 in plate 32. The purpose of the pin and slot connections 57, 58, is to provide a driving connection between the gear 28 and shaft 59 the lower end of which shaft

59 carries the yoke 37 and discs 39, 40 for causing the threads 25, 25' to be wrapped around selected needles. Ordinarily and as disclosed in the Lawson Patent 1,702,608, the means corresponding to the disc 39, 40 rotates one and one with the needle cylinder, and due to the fact that the needle cylinder is of much greater diameter than the diameter of the plates 39, 40, the needles relatively move past the threads 25, 25' and it is not possible to wrap threads of different colors around immediately adjacent needles during the same course of knitting because adjacent guide eyes 38, 38' must necessarily be spaced apart a greater number of degrees than the number of degrees measured between two adjacent needles; accordingly, some means must be provided whereby an eyelet such as the eyelet 38 may wrap its thread 25 around one or more groups 60 consisting of one or more selected needles (Fig. 10) and thereafter eyelet 38' may wrap its thread 25' around other and adjacent groups 61 of selected needles (Fig. 11). As shown in Figs. 10 and 11, the needles 60 wrapped with thread 25 include three groups of two needles each, said groups being separated by other groups of two needles 61 each, which latter are wrapped with thread 25'.

The object of wrapping immediately adjacent needles by threads of different colors during the same course of knitting is accomplished by the method of selecting and controlling needles hereinafter described and assisted by the hereinbefore described detents 53 which for the greater part of the revolution merely act as driving connections between the gear 28 and the shaft 59; but when the eyelets 38, 38' reach the position shown in Figs. 5, 6 and 7, they are momentarily held in such position and until the threads 25, 25' are wrapped around their respective groups of needles 60, 61, the retardation of the discs 39, 40 and shaft 59 being accomplished by an abutment 62 depending from and fastened to the flanged ring 41. In Fig. 4, one detent 53 is shown as just having moved into engagement with the abutment 62. Engagement of the abutment 62 with a detent 53 causes the end of the latter to seat against such abutment and remain there until, due to the rotation of the gear 28 and connected parts, the pivot pin or screw 52 is moved to the position shown in Fig. 4a, when further rotation of the gear 28 and connected parts causes the end of the detent 53 to slip off the abutment 62; whereupon the coil spring 55, which was elongated by the engagement of the detent 53 with the abutment 62 and the rotation of the gear 28 and connected parts, causes the detent 53 to snap off the abutment 62, thus rotating the shaft 59 through the engagement of the pin 57 with the slot 58. When the detent 53 is released from the abutment 62 the coil spring 55 tends to pull the detent in a counter-clockwise direction (Fig. 4a) which detent by means of its pin 57 engaging the wall of the slot 58 causes the plate 32 which is provided with slots 58, also to move quickly in the counter-clockwise direction (Fig. 4a) and the movement of the plate 32 is communicated to the shaft 59 through the block or plate 33 which latter is provided with a spline 63 engaging in a longitudinally disposed keyway 64 provided in the shaft 59, such spline and keyway connection transmitting rotary movements from the gear 28 to the shaft 59, but permitting the wrapping mechanism to be elevated at desired times as by means

of a lever similar to the lever 120 in the Lawson Patent 1,702,608 and connections therefrom.

The method of wrapping immediately adjacent needles with threads of different colors is illustrated in Figs. 5-11 inclusive to which reference is now made. As shown in said figures, pairs of eyelets 38, 38' are disposed at opposite sides of the discs 39, 40 whereby clocking or other effects may be knitted into a stocking or other fabric at opposite sides thereof. However, the number and disposition of the guides such as 38, 38' is not restricted and may be varied according to the pattern desired.

As shown in Fig. 5, the latch ring 16 is recessed at 65 thereby permitting the discs 39, 40 to overlap the needle cylinder so that the eyelets 38, 38' may pass to the outside of the needle circle during their needle wrapping movements. As hereinbefore stated the needles 23 which are mounted in tricks or grooves in the needle cylinder 1, as well as the discs 39, 40, are driven through the connections hereinbefore described in the direction of the arrows, Fig. 5, so as to rotate one and one, that is, one turn of the needle cylinder for one turn of the discs 39, 40. When, during the relative rotations of the needle cylinder 1 and guides 39, 40, they arrive at the relative positions shown in Fig. 5, a detent 53 has just reached the position shown in Fig. 4, that is, in engagement with the abutment 62. Thereafter rotation of the needle cylinder continues from the position shown in Fig. 5 to that shown in Fig. 7 without the discs 39, 40 rotating. During this interval, i. e., from Fig. 5 to Fig. 7, the groups 60 of the needles are elevated by any one or more of the cams 4 and immediately thereafter one or more of the cams 5 elevate groups 61 of needles, whereby the groups 60, 61 of needles may be wrapped by threads 25, 25' respectively.

It will be understood from inspection of Figs. 5-11 inclusive, that the wrapping of immediately adjacent needles by threads of different colors is rendered possible by the fact that the needles or rather the groups 61 of the needles 23 are not elevated by the jacks and cam or cams 5 as indicated by dot and dash line 66 until after the said needles have moved past the eyelet 38; and that the groups 60 of the needles 23 are raised as indicated by dot and dash line 67 just before they reach the eyelet 38 and after engaging the thread 25 in their hooks are immediately lowered by cam 14 so as not to engage the thread 25' which is fed to the groups 61 of the needles 23 through the eyelet 38'.

After the groups of needles 60, 61 have been wrapped by their respective threads 25, 25' a detent 53 snaps off the abutment 62 thereby causing the discs 39, 40 through the connections hereinbefore described to move quickly from the position shown in Fig. 7 to that shown in Fig. 8; in other words, the spring 55 companion to the detent 53 causes the discs 39, 40 to catch up with the needle cylinder. The quick circumferential movement of the discs 39, 40 just described prevents any possibility of the second thread 25 being wrapped around the needles 61. Thereafter and until the other detent 53 engages the abutment 62, the discs 39, 40 and needle cylinder rotate in time the one with the other; engagement of the detent 53 with the abutment 62 causing the operations just described to be repeated.

In Figs. 6-9 inclusive there is shown a fragment 68 of the so-called binder plate which corresponds to the plate 280 shown in Lawson Patent

1,702,608 and upon the upper surface of which is mounted the usual means for clamping and severing the yarns 20, 21, 22, etc., when the latter are to be interchanged the one for the other 5 whenever it is desired to change the said yarns during the knitting of the stocking as, for example, when commencing the knitting of the heel and toe. The plate 68 is provided with an elongated extension or finger 69, providing therebetween and the opposing edge of the plate 68 a slot 70 corresponding in function to the slot 281 shown in the Lawson Patent 1,702,608. During the knitting of wrap courses the wrap thread such as 25, 25' "play" in the said slot 70 within 15 which they are confined, additionally if desired, by means of a member similar to that shown at 282 in the Lawson Patent 1,702,608. After the wrap threads are engaged in the needle hooks, continued rotation of the needle cylinder draws 20 out the said wrap threads while the wrapped needles and companion eyelets 38, 38' are relatively moving away from one another or separating, and thereafter when the said needles and companion eyelets 38, 38' relatively approach one another, take-ups similar to or identical with 25 the take-ups disclosed in the Lawson Patent 1,702,608 take up the resultant slack in the threads 25, 25'. As the needles and eyelets 38, 38' move in the direction of the arrows, Fig. 5, 30 the groups 60, 61 of needles 23 engage their respective threads in their hooks and thereafter, due to the rotation of the needle cylinder relatively to the binder plate 68, carry such threads around to a position adjacent to the end of the finger 69 where a member similar in construction and function to the member 282 shown in the Lawson Patent 1,702,608 engages such threads and as the needle cylinder continues its rotation causes such threads to be confined within 35 the slot or opening 70, such threads when the eyelets 38, 38' again reach the position shown in Fig. 5, leading as floats from the wales where they were knitted into the fabric during the mentioned preceding course of knitting, under the finger 69 and then up above the same and through the eyelets 38, 38'. During the next course of knitting the threads 25, 25' are again fed to selected needles which thereafter continue 40 their rotation as before and during such rotation cause the floats of threads 25, 25' leading from the fabric, underneath the finger 69 and up over the same to the needles last engaging the same, to be drawn off the finger 69. Successive positions of such threads are indicated in the drawings: in Fig. 9 the threads 25, 25' are shown after 45 the knitting of one course and prior to the knitting of the following course; in Fig. 6 the same parts and threads are shown in a later phase of the knitting cycle; in Fig. 7 the parts and threads are shown in a still later phase; and in Fig. 8 the parts and threads are shown in a still later phase, the threads being just about 50 to pass off the end of the finger 69.

In Fig. 12 there is shown a stocking or half-hose 71 having clocking effects 72 knitted into the leg thereof, such clocking effects consisting of some of the stitches 73 in some of the courses having knitted therein a wrap thread of one color or characteristic, and other stitches 74 of the 55 courses having knitted therein a wrap thread of a different color or characteristic. The stitches 73 are shown as varying in number from course to course. During the knitting of the stocking or half-hose a heel 75 and toe 76 are knitted, the main yarns being changed at the commence- 60

ment of the knitting of the heel and toe and at the completion of the knitting thereof, such interchange of yarns being accomplished by means of the yarn levers 17, 18, 19 and the yarn clamping and cutting mechanism disclosed in the Lawson Patent 1,702,608, which clamping and cutting mechanism is, preferably, mounted upon the upper surface of the plate 68.

The use of the mechanism hereinbefore described for wrapping immediately adjacent needles during the knitting of a course, in connection with the interchangeable yarn levers and clamping and cutting mechanism, renders it possible to knit a stocking or half-hose having different wrap threads knitted therein at adjacent wales in the same course or courses; and having knitted therein different main or body yarns such as for the heels and toes, although horizontal stripes could obviously be knitted into leg or foot of a stocking or half-hose if desired.

The wrapping and needle selection mechanism hereinbefore described, makes it possible to wrap one or more needles with one thread only and to wrap immediately adjacent needles on either or both sides of the needles first mentioned with a second thread only.

In other words, needles of the groups 60, 61 (Fig. 10) may be optionally wrapped, dependent upon needle selection, with either of the two threads 25, 25'. Where, in the foregoing description, reference is made to the wrapping of adjacent or other needles with different threads, it will be understood that the language is intended to define the wrapping of at least one needle with one thread only and an immediately adjacent needle with another thread only. Furthermore, where wrapping needles with one thread only is referred to it is the intention to cover the wrapping of two or more threads when they are fed to the needles through a single eyelet 38, 38'; and where the selecting of a group of needles is referred to, it is the intention to include the wrapping of single needles or a plurality of needles, as determined by needle selection.

Although in the foregoing description limiting terms have been used to describe the various parts and functions of the same, there is no intention to limit the invention to the precise details disclosed nor to the type of machine disclosed, the invention being applicable to types of machines other than the Banner machine to which this invention particularly relates; it being the intention to limit the invention by the appended claims only.

This application is a continuation of application Ser. No. 552,954, filed July 24, 1931.

I claim:

1. A circular knitting machine having a rotary needle cylinder in which needles are independently mounted, means for feeding at least one yarn to all of the needles, means for wrapping at least two differently colored threads around selected needles, said wrapping means being mounted to rotate in time with the needle cylinder but in eccentric relation therewith, and means for selecting needles to be wrapped with each of the threads, the needle wrapping being selectively controlled variably to wrap one or more needles with one thread only and to wrap, during the same course of knitting, needles immediately adjacent to the variably wrapped needles with another thread only, whereby a color within color effect is produced in a given course.

2. A circular knitting machine having a rotary needle cylinder and needles independently mount-

ed therein, means for feeding at least one yarn to all of the needles, means for wrapping at least two threads around selected needles, said wrapping means being mounted to rotate in time with

5 the needle cylinder but in eccentric relation therewith, and means for selecting needles to be wrapped with each of the threads including a plurality of needle selecting stations at each of which stations needles are selected to be wrapped with

10 one of the threads, the needle wrapping being selectively controlled variably to wrap one or more needles with one thread only and to wrap at least one needle immediately adjacent to the variably wrapped needle or needles with another thread

15 only so that during a given course of knitting one, at least, of the needles shall be wrapped with one of the threads only and an immediately adjacent needle shall be wrapped with another thread only.

20 3. A circular knitting machine of the independent needle type having a needle cylinder, means for feeding at least one yarn to all of the needles during the knitting of a plurality of courses, means, between which and the needle

25 cylinder there are relative rotary movements, to wrap one thread around one or more of a group of needles and another thread around one or more of another group of needles and in such a manner that immediately adjacent needles may be wrapped, during the same course of knitting, with threads having different characteristics, in combination with means including a plurality of needle selecting stations each needle selecting station selecting one of the groups of needles.

35 4. A circular knitting machine of the independent needle type having a rotary needle cylinder and means for feeding at least one yarn to all of the needles during the knitting of a plurality of courses, means adapted to rotate in time

40 with the needle cylinder but at a lesser linear velocity with respect thereto, such other means including thread guides moving during the knitting of wrap courses and while the said means is rotating, from a position within the needle circle

45 to a position outside thereof, the wrapping being so controlled as, during the knitting of the same course, to wrap one or more needles of one group of needles with one thread and to wrap one or more needles of another group of needles with a second thread so that two immediately adjacent needles may be wrapped with separate threads each having different characteristics, in combination with means including a plurality of selecting stations each of which variably selects one of the groups of needles.

55 5. In a circular, independent needle knitting machine having a rotary needle cylinder, means for feeding at least one yarn to the needles, means for wrapping differently colored threads around

60 needles said wrapping means including a wrapping head rotatable in time with the needle cylinder but in eccentric relation therewith so as to cause the threads to move from a position within the needle circle to a position to the outside thereof and back again to a position within the needle circle, said wrapping means wrapping at least two threads around selected needles, one such thread being variably wrapped around one or more needles as desired, the needle wrapping

65 being so controlled that during a given course of knitting one or more needles shall be wrapped with one thread only and at least two needles immediately adjacent to and on each side of the said one or more needles shall be wrapped with a second thread only, whereby in a course a color

within color effect will be produced, in combination with a plurality of needle selecting stations each variably selecting needles to be wrapped with one of the threads.

6. In a circular, independent needle knitting machine having a rotary needle cylinder, means for feeding at least one yarn to the needles, means for wrapping differently colored threads around needles said wrapping means including a wrapping head rotatable in time with the needle cylinder but in eccentric relation therewith so as to cause the threads to move from a position within the needle circle to a position to the outside thereof and back again to a position within the needle

circle, said wrapping means wrapping at least two threads around selected needles, one such thread being variably wrapped around one or more needles as desired, the needle wrapping being so controlled that during a given course of knitting one or more needles of a group of needles shall be wrapped with one thread only and one or more other needles of a group shall be wrapped with a second thread only, whereby in a course a color within color effect will be produced, in combination with a plurality of needle selecting stations each variably selecting needles to be wrapped with one of the threads.

ROBERT H. LAWSON.
